UNITED STATES PATENT OFFICE.

WARREN CHALMERS REES, OF SOMERVILLE, MASSACHUSETTS, ASSIGNOR TO ASEPTIC SERVICE COMPANY, OF BOSTON, MASSACHUSETTS, A CORPORATION OF MAINE.

COUNTER-OPERATING MECHANISM FOR COIN-CONTROLLED DEVICES.

1,396,342.

Specification of Letters Patent.

Patented Nov. 8, 1921.

Application filed August 11, 1920. Serial No. 402,870.

To all whom it may concern:

Be it known that I, WARREN C. REES, a citizen of the United States, residing at Somerville, in the county of Middlesex and State of Massachusetts, have invented new and useful Improvements in Counter-Operating Mechanism for Coin-Controlled Devices, of which the following is a specification.

10 This invention relates to a coin-controlled device adapted, for example, to be used in operating the lock or latch of a door. For illustration of the present invention, I have chosen the device disclosed by the Morse 15 Patent No. 1,148,249, dated July 27, 1915, the embodiment of the invention here shown being designed with particular reference to its applicability to that device, but it is to be understood that in so illustrating the 20 invention hereinafter described, I have not intended to limit its application to a device for the particular use for which the said patented device is adapted.

The object of the invention is to provide 25 in a coin-controlled device a mechanical counter, which is operable, to register the number of coins inserted, partially by the forcible insertion of the coin in the slot of the device, and partially by a manual movement of a member of the device, causing said member to perform its usual function, (which may be that of releasing the coin), and the additional function of partly operating the counter.

30 The invention is embodied in a coin-controlled device provided with a mechanical counter, preferably of the so-called Veeder type, having an oscillatory arm, and counter-operating mechanism adapted, by oscillating 35 said arm, to cause the counter to register, said mechanism including means operable by force exerted through a coin pushed into a coin-receiving slot by an operator, to move the counter arm in one direction, and means 40 manually operable from the exterior of the casing to move the counter arm in the opposite direction, said manually operable means, in this embodiment of the invention, including one of the heads employed in the 45 patented Morse device to alternately arrest and release a coin, said head having, therefore, a dual function.

I will now describe the herein illustrated embodiment of the invention, in connection

with the drawings which accompany and 55 form a part of this specification.

Figure 1 is an elevation of the patented Morse device as applied to a door in connection with a lock on such door, a portion of the casing being in section to show the coin 60 slot and one of the members of the counter-operating mechanism of my invention.

Fig. 2 is a top plan view of the device as shown by Fig. 1, the door and lock being 65 omitted.

Fig. 3 is a front elevation, showing the casing opened.

Fig. 4 is an enlargement of a portion of Fig. 3, showing the upper part of the fixed portion of the casing, and omitting the head 70 associated with said fixed portion.

Fig. 5 is a fragmentary section on line 5—5 of Fig. 4.

Fig. 6 is a perspective view of the biased counter-arm-engaging member. 75

Fig. 7 is a perspective view of the supporting bracket hereinafter referred to.

Fig. 8 is a fragmentary view, showing in section, a portion of the case on line 8—8 of Fig. 3, and in elevation, certain parts 80 above said line.

Figs. 9 and 10 are views similar to Fig. 4, illustrating different stages of the operation.

Fig. 11 is a section on line 11—11 of Fig. 4.

Fig. 12 is a section on line 12—12 of Fig. 9. 85

Fig. 13 is a section on line 13—13 of Fig. 10.

The same reference characters indicate the same parts in all of the figures.

The casing consists of a body 10, and a 90 cover 11, connected to the body by hinges 12. The body 10 may be attached to a door 14 having mounted upon it a lock 17. In the body 10 is a bearing 20, and in the cover 11, is a bearing 21. In these bearings 95 are journaled shanks or shafts 22 and 23 respectively, the former passing through the lock and being engaged with the latch bolt and having an operating handle 24, the other shank having an operating handle 25. Rotation of the shank 22 causes the retraction of the latch bolt, and also causes the release of a coin previously inserted in the casing, the shank 22 being provided with a head 26, having a shoulder 32, and the shank 100 23 being provided with a head 27, having a shoulder 33. These heads and shoulders act as described in the Morse patent, to alter-

nately arrest and release a coin, the release being effected by a partial rotation of the head 26 from the position shown by Figs. 3, 9 and 10, in the direction of the arrow 5 on Fig. 10.

For a more complete description of the operation of the mechanism thus far described, reference may be had to the above-mentioned patent.

I will now describe the features that characterize the present invention. Fixed to, and located within the casing body 10, is a cyclometer or mechanical counter, preferably of the well known Veeder type disclosed by Letters Patent No. 548,482, dated October 22, 1895. The said counter includes a holder 35, attached to the body 10 and having a sight aperture 36, an actuating rock-shaft 37, journaled in the holder, and a series of index wheels 38, mounted to rotate step-by-step in the holder, means being provided, as shown by the said Veeder patent for actuating the first of said wheels from the rock-shaft, and each of said wheels from the next in order. The counter rock-shaft 37 is provided with an arm 40 formed to contact with, and be oscillated by, the hereinafter described members of a counter-operating mechanism, the counter being located adjacent to the coin-receiving slot 31 in the top of the casing.

The coin slot is preferably formed in the cover 11 of the casing, said cover having an ear or lip 42 overlapping a part of the casing body 10, and covering a recess 43 into which the slot 31 opens, as shown by Fig. 1.

Located within the casing in position to obstruct the coin slot 31 is a biased counter-arm-engaging member, which is preferably a bell-crank lever, indicated as a whole by the reference numeral 44 (Fig. 6), said lever including a slot-obstructing outer arm 45, an inner arm 46 contacting with the counter arm 40, a hub 47 journaled on a fixed stud 48, and an arm 49 connected by a biasing spring 50 with a fixed ear 51. The member or lever 44 is normally held by the spring 50 in the position shown by Figs. 3, 4 and 10 so that its outer arm 45 is in the path of a coin 52, and is adapted to be displaced by force exerted by the operator, through the coin, to the position shown by Fig. 9, the inner arm 46 being thus moved to swing the counter arm 40 to the raised position shown by Fig. 12, and thus partially operate the counter. When the coin passes the arm 45, the lever of which said arm forms a part is returned by the spring 50 to its normal position, leaving the counter arm 40 in its raised position, as shown by Fig. 10.

Pivoted at 55 to a fixed support in the casing, is an unbiased counter-arm engaging member, which is preferably a bell-crank lever composed of an outer arm 56, 65 contacting with the counter arm 40, and an

inner arm 57, arranged to be moved by the head 26, when the latter is manually moved to release the coin after the function of the coin has been performed, as described by the Morse patent. The arm 57 is in the path of a stud 58 fixed to the head 26, the arrangement being such that when the stud is moved from the position in the direction of the arrow in Fig. 10 from the direction there shown, the unbiased lever is moved to swing the counter-arm downward to the position shown by Figs. 3, 4, 5 and 11, and thus complete the operation of the counter. Owing to the fact that the lever formed by the arms 56 and 57 is unbiased, and remains in any position to which it is movable, said lever remains in the position shown by Figs. 9 and 10, after the return of the biased lever 47 to its normal position, until moved to the position shown by Figs. 3 and 4 by the stud 58.

To enable the arm 57 to yieldingly encounter the stud 58, I provide said arm with a resilient abutment 60 for said stud, and thus compensate for the different directions of movement of the lever-arm and the stud.

It will now be seen that the counter is operated partly by force exerted on the coin by the operator in inserting the coin in the slot, and partly by force exerted by the operator on the head 26 in releasing the coin.

The counter-arm 40 is preferably provided with an inclined edge face 40^a, with which the biased lever arm 46 is in sliding contact, and with a hooked finger 40^b contacting with the unbiased lever arm 56.

I claim:

1. In a coin-controlled device, the combination of a casing having a coin receiving slot, a mechanical counter provided with an oscillatory arm adjacent to said slot, and counter-operating mechanism adapted to operate the counter by oscillating the arm thereof, said mechanism including a biased counter-arm engaging member normally obstructing the slot, displaceable by force exerted through a coin inserted in the slot, and engaging the counter arm to move the latter in one direction, a coin-releasing member operable from the exterior of the casing, and an unbiased arm-engaging member, movable by force exerted through said coin-releasing member to move the counter-arm in the opposite direction, the counter-arm being formed to coöperate with the members contacting therewith, said unbiased member being movable alternately by the counter-arm and by the coin-releasing member.

2. A coin-controlled mechanism embodying the combination specified by claim 1, the said biased member being a bell-crank lever having an outer arm normally obstructing the coin slot, and an inner arm contacting with the counter-arm.

3. A coin-controlled mechanism embodying the combination specified by claim 1, the

said unbiased member being a bell-crank lever having an outer arm contacting with the counter-arm, and an inner arm arranged to be moved by the coin-releasing member.

5 4. A coin-controlled mechanism embodying the combination specified by claim 1, the said coin-releasing member being oscillatable in a bearing in the casing and provided with a laterally projecting stud, and

the said unbiased member being a bell- 10 crank lever having an outer arm contacting with the counter-arm, and an inner arm located in the path of said stud, and provided with a yielding abutment for the stud.

In testimony whereof I have affixed my 15 signature.

WARREN CHALMERS REES.
